UNITED STATES PATENT OFFICE.

GEORGE A. BURNHAM, OF CLIFTONDALE, MASSACHUSETTS, ASSIGNOR TO SEARS B. CONDIT, JR., OF BROOKLINE, MASSACHUSETTS.

SERIES TRANSFORMER.

1,138,625.

Specification of Letters Patent. Patented May 11, 1915.

Original application filed February 8, 1911, Serial No. 607,368. Divided and this application filed October 16, 1911. Serial No. 654,838.

To all whom it may concern:

Be it known that I, GEORGE A. BURNHAM, a citizen of the United States, residing at Cliftondale, in the county of Essex and 5 State of Massachusetts, have invented certain new and useful Improvements in Series Transformers, of which the following is a full, clear, and exact specification.

This invention relates to series transformers, the object being to preserve a constant ratio of transformation and to prevent damage to the windings or to the instruments supplied by the transformer by excessive rise of voltage in the secondary circuit. To 10 this end I preferably employ an auxiliary closed circuited winding around the core, by which the ratio of transformation is held constant, and in the secondary circuit I place the various types of translating devices to 15 be operated, such as measuring instruments, trip coils of circuit breakers, or other switchboard apparatus requiring a low tension alternating current, I protect the transformer from damage by an automatic 20 switch operating on excessive rise of voltage in the secondary circuit. The secondary is normally a low tension circuit, but its potential is subject to wide changes under certain abnormal operating conditions, and especially on open circuit conditions or when 25 the resistance is greatly increased. Under such circumstances the transformer becomes dangerously hot and destroys the insulation producing a cross connection with the low- 30 potential apparatus, which leads to disastrous results. I provide means for cutting out the transformer under dangerous conditions by opening the supply switch.

This application is a division of my parent application, No. 607,368, filed Feb. 8, 1911, which fully sets forth the advantages of my improvements in maintaining the ratio of transformation. The present application is restricted to the control of the supply 40 circuit for the transformer, so that it may be cut out under dangerous conditions.

In the accompanying drawings, Figure 1 shows diagrammatically protective apparatus embodying my improvements. Fig. 2 45 shows another form of the same.

1 represents a series transformer having primary coil 2 and a secondary coil 3. Such transformers commonly have a high ratio of transformation and consist of an iron core 4

with a few turns of primary winding supplied by the high tension wires of the distribution system. The secondary coil 3 has generally a greater number of turns linking the same magnetic circuit and is carefully insulated from the primary winding. The 55 ratio of transformation is governed by the relative number of turns of the two windings. In the primary winding there may be an extremely high voltage, but the voltage of the secondary winding is very low, being 60 only sufficient to force the proper amount of current through the indicating or recording instruments; therefore the high potential of the line which is dangerous to life is kept 65 away from the switch-board.

The load carried by the secondary circuit is composed of electrical measuring instruments, one of which is indicated at 5, trip coils of circuit breakers, or other switchboard translating devices requiring a low 70 potential current. In the case of a 20 to 1 ratio of transformation I make the primary of two layers of 15 turns each, which may be connected in series or parallel to supply different loads, and give the secondary 75 240 turns. A closed compensating circuit 6 maintains the ratio constant under wide load ranges so that the measuring instruments are free from error due to a falling off of the current curve under such changes 80 of load. This compensating coil is of low 85 resistance and which may be adjustable; it may be used to supply the trip coil 7 of the 90 automatic switch or the latter may be operated by the secondary circuit as in Fig. 2. With change of load in the secondary, such an auxiliary coil holds the ratio of transformation practically constant.

It is exceedingly important that the transformers should be cut out of circuit when 95 unusual conditions arise in the secondary, since the excessive heat of the transformer will soon destroy it if the resistance of the secondary is greatly increased. In Fig. 1 I show means for opening the main circuit of 100 the transformer through an increased current flow in the compensating coil. In case the resistance of the secondary circuit increases unduly, which may follow from a loose connection of some of the translating 105 devices or other cause, the entire load will be thrown on the compensating coil and the trip coil excited to open the switch.

In Fig. 2 the trip coil which operates the switch is supplied by the secondary of the transformer. In this arrangement, the switch is opened in case of overload in the primary circuit, and is also protected from excessive rise of voltage in the secondary circuit. The secondary supplies the trip coil, and a small relay 8 is placed in the compensating circuit. If the transformer is 10 excessively loaded, the automatic switch having the trip coil 7 will be opened; or if there should be a break in the external secondary circuit or any other trouble that would create an improper rise of secondary 15 voltage the relay will automatically close the secondary circuit at a point near the transformer and hold the load constant thus preventing damage to the transformer.

Having thus described my invention what 20 I claim as new and desire to secure by Letters Patent is:

1. The combination of a series transformer having a primary and a secondary normally deriving energy from the primary, 25 a circuit connected to the primary, a switch in the primary circuit, a coil in inductive relation to the transformer primary and secondary, and means controlled by said coil and responsive to wide changes of resistance 30 and resultant excessive rise of voltage in the secondary for opening the switch.

2. The combination with a series transformer having a primary and a secondary normally deriving energy from the primary, 25 of a circuit to which the primary is connected, an automatic switch in said circuit, a trip coil receiving its energy inductively from the transformer primary for opening

the switch on overload, a coil in inductive relation to the transformer primary and secondary, and means controlled by the last mentioned coil for short-circuiting the secondary circuit upon excessive rise of resistance in the external secondary circuit. 40

3. The combination with a series transformer having a primary circuit and a secondary circuit normally fed therefrom, of a coil in inductive relation to the primary and secondary of the transformer and means controlled by said coil for preventing excessive 45 rise of voltage in the secondary circuit. 50

4. A series transformer having a primary winding, a secondary winding, and a closed coil on said transformer adapted to preserve its ratio of transformation under change of 55 load, and means controlled by said coil for preventing excessive rise of voltage in the secondary circuit.

5. The combination with a series transformer having a primary winding, a secondary winding, and a closed coil on said transformer adapted to preserve its ratio of transformation under change of load, of means controlled by said coil for preventing excessive rise of voltage in the secondary 60 circuit, comprising an automatic switch in the primary circuit, and an overload trip coil for said switch receiving its energy inductively from the transformer primary. 65

In testimony whereof I affix my signature, 70 in presence of two witnesses.

GEORGE A. BURNHAM.
